EARTH MOVING DEVICE

Ellsworth W. Austin, Cedar Rapids, Iowa, assignor, by mesne assignments, to Killefer Manufacturing Corporation, a corporation of California

Application September 21, 1935, Serial No. 41,574

8 Claims. (Cl. 37—149)

This invention relates to earth moving devices and has particular relation to a device of the so-called roll-over scraper type in which earth is dug by a scraper blade and deposited in a bowl and in which the material is discharged by permitting the bowl to roll on the ground.

It is desirable in scrapers of this character that means be provided for decreasing and increasing the angle of attack of the cutting blade as the digging effort required becomes harder or easier and decreasing the angle when the bowl is filled with material.

In the devices of the prior art this has been accomplished by providing a lever mechanism which rolls the bowl of the scraper forward and backward in its bowl engaging structure as the digging became easier or harder.

In my present invention I propose to tilt both the bowl engaging structure and the bowl as a unit thus avoiding the necessity for the complicated, expensive and unreliable lever and linking mechanism necessary in the devices of the prior art.

It is the general object of my invention to provide a scraper of the so-called roll-over type in which the angle of attack of the cutting edge is varied inversely in accordance with the drawbar pull on the scraper.

Another object of my invention is to provide an improved scraper structure which eliminates many parts previously found necessary.

Another object of my invention is to provide a new and novel mode of operation of such a scraper whereby many parts hitherto found necessary may be eliminated.

Another object of my invention is to provide a resilient means for counteracting the pull on the scraper blade.

Another object of my invention is to provide means for housing the operating and control mechanism of such a scraper.

Another object of my invention is to provide means for varying the coupling of the scraper to the tongue or drawbar by which the scraper is towed.

Another object of my invention is to provide an improved operating and actuating mechanism for scrapers of this character.

Other and further features and objects of the invention will be more apparent to those skilled in the art upon a consideration of the accompanying drawing and following specification, wherein is disclosed a single exemplary embodiment of the invention, with the understanding, however, that such changes may be made therein as fall

within the scope of the appended claims, without departing from the spirit of the invention.

In said drawing:

Figure 1 is a view in perspective of an earth moving device constructed according to my invention as it appears in normal or cutting condition before being loaded with earth.

Figure 2 is another view in perspective of the device shown in Figure 1 as it appears while in operation in picking up a load of earth.

Figure 3 is a fragmentary view in perspective of one of the bowl latching members of the scraper.

Figure 4 is a view partly in the elevation and partly in sections of the shock absorbing mechanism of the device shown in Figures 1 and 2, and

Figure 5 is a fragmentary plan view of the adjustable connections by which the pivot arms are connected to the pivot plates.

Referring now to the drawing and more particularly to Figures 1 and 2 thereof, a preferred form of roll-over scraper constructed according to my invention consists of a bowl 10, a tongue and drawbar assembly 11 and means indicated at 12 for operating and actuating the scraper, including means for tilting the bowl in accordance with the cutting resistance.

The bowl is of more or less standard construction and employs a pair of disk-like end members or heads 13 and 14 connected by a semi-cylindrical plate 16. This semi-cylindrical plate, or bowl sheet as it may be termed, is suitably braced by means of a longitudinal flange 17 and a plurality of angle braces or ribs 18. The ribs 18 not only serve to brace the bowl and connect the bowl with the heads 13 and 14 but also serve as a means of engaging and supporting a cutting blade 19. The heads 13 and 14 support inwardly extending curved plates or shoes 21 and 22, and these shoes serve to support the bowl when it is being dumped, the bowl sliding on these shoes while in that position.

A portion of each of the heads 13 and 14 is flattened as indicated at 23 adjacent the cutting blade 19 so that the blade, together with the adjacent portion of the bowl sheet 16 and the flat portions of the heads 13 and 14, form a flat surface for supporting the bowl as it moves over the ground while in the cutting position. The heads 13 and 14 are reinforced at their centers by means of the reinforcing plates 24 and 26. Heavy bolts 27 and 28 pass through the centers of the heads 13 and 14, through the reinforcing plates 24 and 26, and through the pivot plates 29 and 31, the outer portion of the bolt being provided with bronze sleeves 30 on which the pivot plates may

freely rotate. The sleeves or bushings 30 are slightly longer than the thickness of the plates 29 and 31 in order that, when the nuts 35 are drawn up, the bolts 27 and 28 and washers 40 will clamp the bushing tightly against the respective plates 24 and 26.

Two sets of bosses or stops 32 and 33 extend outwardly on either side from the heads 13 and 14, also for a purpose to be hereinafter explained.

The pivot plates 29 and 31 are utilized in pushing and pulling the bowl about over the surface of the ground and these pivot plates are connected to a pair of forwardly extending bowl 15 pivot arms 34 and 36. The adjacent portions of the pivot arms 34 and 36 and of the pivot plates 29 and 31 are vertically toothed as indicated at 37 and the pivot plates are slotted as indicated at 38 in order that the combined arm, formed by 20 the pivot arms and the pivot plates, may be lengthened or shortened as desired to permit the bowl to be tilted or shifted slightly about its longitudinal axis with reference to the tongue to vary the normal angle of attack of the cutting 25 blade. Lengthening the combined arm formed by the pivot plates and pivot arms will cause the angle of attack of the cutting blade to be increased. Shortening the combined arm will cause a decrease in the angle of attack of the cutting 30 blade. The pivot plates and pivot arms are secured to each other by means of bolts 39.

The bowl pivot arms 36 are secured by means of bolts 41 to a pair of upright triangular plates 42 and also to a pair of inwardly and forwardly 35 extending tie members 43. The tie members 43 converge inwardly and are secured on opposite sides of a tongue 44 by means of a bolt or pivot pin 46. The tongue 44 is preferably a hollow structural steel member open at the forward and rear ends thereof. A pair of tubular members, which may be termed the cross tubes or torque tubes 45 and 47, are welded at their inner 40 ends 48 to opposite sides of the rear end of the tongue 44 and the outer ends of these tubes are engaged to the respective plates 42 as by welding 45 them to the plates. The tubes are also secured to the tongue by means of bracing members or gussets 49. The tubes serve as pivots for the upper ends of links 51.

50 The upper rear end of the tongue 44 is slotted as indicated at 51 in order to receive a trip lever 52 within the tongue and this trip lever is actuated by an operator on the towing vehicle 53 by means of a rope 54. An upwardly projecting post 56 is provided on the upper face of the tongue 44 and a clevis 57 is attached to the trip lever 52 together with a spring 58 to hold the trip lever 52 normally in a rearward position as indicated in Figure 1. The lower end of the trip 55 lever 52 is secured on a trip shaft 61 and pulling the rope 54 rotates this trip shaft to raise latch arms 62, one on each end of the bowl, to disengage the latches 64 from the stops 32 or 33.

The latches 64, provided on the ends of the 56 latch arms 62, are removable. It is sometimes desirable that these latches be removed to permit the bowl to rotate or in order that the latches may be readily replaced when they become worn. Releasing the pull rope 54 of course permits the latches to drop down to cause them to engage the stops 32 or 33. These latches are so arranged that when the pull rope is pulled the bowl may rotate in either direction but when it is released the trip lever 52 will strike the 60 stop 56 permitting the latches to drop into the

path of the stops 32 and 33 but preventing them from dropping below that path. When the bowl is rotated forward or backward it may rotate until the stops 32 or 33 engage the latches thus permitting the operator to hold the bowl in 5 "digging" or "bulldozing" position.

The tongue 44 is secured to the drawbar by means of two sets of links 71 and 72. The links 71 are comparatively short and forward movement of the drawbar 11, with reference to the 10 tongue 44, results in very little or no spreading apart of the rear ends of the tongue and drawbar. The links 72 are approximately twice as long as the links 71 and when the drawbar 11 is pulled the forward motion of the drawbar results 15 in rotation of the links 71 and 72 and raising of the front end of the tongue 44 to a greater extent than the rear end is raised. It is of course understood that if the links 71 were of the same length as links 72, the front end of the tongue 20 would be raised appreciably but to a lesser extent than in the case of my preferred arrangement.

Now since the position of the bowl 10 and the cutting edge 19 is determined by the position of 25 the tongue 44 because the tongue while in the digging position is directly connected to the bowl through the agency of the tie members 43, pivot arms 36 and latch arms 31, any tilting of the tongue 44 about a transverse axis will result in 30 rotating the bowl about its longitudinal axis. That is, raising of the front end of the tongue 44 to a greater extent than the rear of the tongue 44 will result in rotating the bowl in a clockwise direction when viewed from the right to thus 35 raise the cutting edge, while a lowering of the front end of the tongue 44 will result in a lowering of the cutting edge. Thus decreasing or increasing the depth of cut is accomplished by raising or lowering the front end of the tongue 40 44. It is apparent that, since the links 72 are longer than the links 71 the more the drawbar 11 is pulled forward with reference to the tongue 44 the greater will be the tilt of the tongue 44 and, consequently, of the bowl 10. 45

It is necessary to provide some resilient means of retarding upward movement of the front end of the tongue 44 since, if no retarding effect was provided, the cutting edge would come out of the ground as soon as a pull was applied to the 50 drawbar 11. This retarding effect is produced by means of a spring 81 which is housed in a cylindrical housing 82, as illustrated in Figure 4. The cylindrical housing 82 is pivotally engaged to the drawbar 11 by means of pivot pins 83 55 which are received in suitable trunnions 84 on the drawbar 11. The housing 82 may thus pivot about on the trunnions 84.

An adjusting screw 86 extends through the center of the coil spring 81 and an adjusting nut 87 engages the forward end of the spring 81 and is threaded on the end of the adjusting screw 86. The adjusting nut 87 may be rotated by means of a long stem 88 which extends sufficiently beyond the housing 82 that it may be rotated 60 by means of a suitable rod (not shown) which may be engaged in the opening 89 in the projecting portion of the adjusting nut. The rear end of the adjusting screw 86 is pivotally engaged to the front end of the tongue 44 by 65 means of the pivot pin 46 which passes through a suitable eye 91 in the rear end of the adjusting screw 86.

The forward end of the drawbar is provided with a toggle member 92 and a swivel 93 in order 70 75

that the scraper may have substantially universal movement with reference to the towing vehicle 52.

In operation the swivel 53 is secured to a towing vehicle such as the tractor 53 and the operator allows the trip rope to be slackened sufficiently to allow the latch arm 62 and the latch 64 to engage the stops 32 on the bowl when the latter rotates in either direction. The tractor 10 is driven forward and the cutting edge 18 of the scraper begins to cut into the earth, thus picking up earth and depositing it in the bowl. As the cutting edge cuts into the earth the pull becomes greater on the drawbar 11 and the drawbar 15 is pulled forward with reference to the tongue 44. As the drawbar is pulled forward the links 72 are rotated to thus raise the front end of the tongue 44 to a greater extent than the rear end. Since the entire bowl and tie 20 members are in effect secured to the tongue 44 this results in decreasing the angle of attack of the cutting edge 18.

Since upward movement of the front end of the tongue 44 also means rearward movement thereof in respect to the drawbar, the adjusting screw 86 is drawn rearwardly against the compression of the spring 81. Thus the greater the resistance met by the cutting edge the more the front end of the tongue 44 is raised but, as the front end of the tongue 44 is raised, more and more resistance to upward movement is encountered by reason of the spring 81 so that finally a position of equilibrium is reached at which the angle of the cutting edge is no longer raised. If, however, harder ground is encountered, the front edge of the tongue 44 is raised still further against the compression of the spring 81 to cause the angle of attack of the cutting edge to be lessened resulting in a smaller cut being taken by 40 the cutting edge. If on the other hand, softer ground is encountered, the front end of the tongue 44 drops under the biasing action of the spring 81 to increase the angle of attack of the cutting edge and therefore increase the depth of 45 the cut. Also as the bowl fills the drawbar pull becomes greater and the adjusting screw 86 and the connections between pivot plates 26 and pivot arms 36 may be so adjusted that the cutting blade tilts further and further upward until, 50 when the bowl is full, the cutting blade is entirely out of the ground.

It is to be observed that most of the operating parts of the machine, particularly those parts in front of the bowl itself, are substantially entirely enclosed. By reference to Figure 2 it is readily understood why this is important since these parts are almost entirely covered by the dirt being carried by the scraper when it is in operation.

60 It is apparent that by my method of tilting the bowl only a relatively few parts are needed and the drag of the scraper can be readily controlled by adjusting the adjusting nut 89. Furthermore, the parts required are simple and of inexpensive construction.

Although I have described a specific embodiment of my invention, it is apparent that modifications thereof may be made by those skilled in the art. Such modifications may be made without departing from the spirit and scope of the invention as set forth in the appended claims.

I claim as my invention:

1. In a scraper, a scraper structure, a tongue secured to the scraper structure and adapted to tilt the scraper structure to vary the angle of

incidence of the cutting edge, a drawbar and substantially parallel differential links at front and rear on the tongue connecting the tongue and drawbar for tilting the tongue with reference to the drawbar, and resilient means for resisting tilting of the tongue with reference to the drawbar.

2. In a scraper including a bucket, a draft means including a tongue and means for rigidly engaging the tongue to the bucket, a drawbar 10 extending beneath the tongue and parallel thereto, a link connecting the rear ends of the tongue and drawbar and a longer link intermediate the length of the drawbar and tongue for pivotally connecting these two members, whereby when 15 loading is applied to the bucket as in digging, the tongue is drawn backward with reference to the drawbar to tilt the tongue with reference to the drawbar to vary the angle of incidence of the cutting edge of the bucket.

3. In a scraper including a bucket, a tongue engaged to the bucket, a drawbar, a spring means pivotally attached to the forward end of the tongue and the forward end of the drawbar whereby a roughly triangularly disposed relation 25 is formed with the tongue as the base of the triangle, the spring means as one short side of the triangle and the drawbar as the other short side and means for causing upward tilting of the two members forming the shorter sides of 30 the triangle to tilt the bucket.

4. In a scraper, a bowl and cutting edge on the bowl, draft means including a yoke member and means for attaching the yoke member in fixed relation with reference to the bowl, the draft 35 means including a tongue extending forwardly from the bowl, a drawbar extending forwardly beneath the tongue and in parallel relation thereto, a link pivotally attaching the rear end of the drawbar to the rear end of the tongue, the link being normally positioned to be inclined forwardly from the drawbar to tongue, a second and longer link disposed forwardly of the first named link and inclined in substantially the same direction as the first named link and inclined in substantially the same direction as the first named link, whereby a load such as the load 40 of the scraper digging in earth draws the tongue rearwardly to tilt the tongue with the front higher than the rear on loading of the 45 bucket to thereby vary the angle of incidence of the cutting edge, a spring pivotally attached to the forward end of the tongue and to the front portion of the drawbar whereby upward movement of the front end of the tongue with reference to the drawbar is resisted with increasing 50 force by the spring.

5. In a scraper, a bowl, a yoke pivotally attached to the bowl, a cross member connecting the sides of the yoke ahead of the bowl, a trip 60 shaft within the cross member protected thereby, a tongue secured on the cross member and extending forwardly therefrom, a trip lever passing downwardly through the tongue and engaged to the trip shaft, trip members on the outer ends 65 of the trip shaft for engaging stops on the bowl, a drawbar beneath the tongue, a link pivotally engaging the drawbar and tongue at the rear of these members, a second and longer link forwardly of the first named link and also pivotally connecting the drawbar and tongue, spring means 70 connecting the forward end of the tongue to the drawbar to resist upward movement thereof with increasing force, the links being arranged so that the greater the load applied to the bowl as in dig- 75

- sing, the more the front end of the tongue is tilted with reference to the drawbar to thereby vary the angle of the incidence of the cutting edge of the bowl.
5. In a scraper, a rotatable bowl, a draft yoke journaled thereon and including a forwardly extending tongue, releasable means for restraining said bowl against rotation with respect to said yoke, a drawbar, means comprising substantially parallel differential links disposed adjacent the front and rear ends of said tongue for connecting the latter to said drawbar and adapted to cause the tongue to tilt relative to the drawbar when a forwardly acting force is applied to the latter and thereby to vary the angle of incidence of the cutting edge of the bowl, and resilient means for resisting said tilting of the tongue relative to the drawbar.
6. A roll-over scraper comprising a rotatable bowl, a draft yoke journaled thereon and including a forwardly extending tongue, a latch arm pivotally supported on said tongue and swingable into engagement with a stop on said bowl to hold the latter against rotation relative to said yoke during scraping operation, a drawbar, means comprising substantially parallel differential links disposed adjacent the front and rear ends of said tongue for connecting the latter to said drawbar and adapted to cause the tongue to tilt relative

to the drawbar when a forwardly acting force is applied to the latter and thereby to vary the angle of incidence of the cutting edge of the bowl, and resilient means for resisting said tilting of the tongue relative to the drawbar.

8. A roll-over scraper comprising a transversely disposed rotatable bowl, a draft yoke including a pair of beams journaled on said bowl at opposite ends thereof, respectively, a transverse tubular member extending between and fixed to said beams, and a forwardly extending draft tongue connected to said beams, a trip shaft rotatably disposed within said tubular member, a latch arm fixed at each end of said trip shaft and rotatable therewith into engagement with stops at opposite ends, respectively, of said bowl to hold the latter against rotation relative to said yoke during scraping operation, a drawbar extending generally parallel to said draft tongue, means comprising fore and aft spaced substantially parallel differential links for connecting said tongue to said drawbar and adapted to cause the tongue to tilt relative to the drawbar when a forwardly acting force is applied to the latter and thereby to vary the angle of incidence of the cutting edge of the bowl, and resilient means for resisting said tilting of the tongue relative to the drawbar.

ELLSWORTH W. AUSTIN.
